AUTOMATIC PUMP SPEED CONTROL

Russell H. Curtis, Dayton, Ohio, assignor to Curtis
Pump Company, Dayton, Ohio, a corporation of
Ohio

Application November 7, 1942, Serial No. 464,901

4 Claims. (Cl. 281—48)

This invention relates to an automatic speed control for a pump, and to a liquid supply system embodying such speed control and a plurality of pumps, the invention being highly desirable for use in connection with the fuel supply for airplanes, although the invention may have other uses and purposes as will be apparent to one skilled in the art.

In fuel supply systems, especially where a booster pump is used in addition to a main or regular fuel pump, it is desirable to maintain a predetermined constant pressure differential between the carburetor intake and the carburetor outlet to the engine being supplied with fuel. The maintenance of that predetermined pressure differential is at times extremely difficult, and this has in the past proven true especially in connection with the fuel systems on airplanes where the ambient air pressure at the fuel tank varies constantly as the plane ascends and descends, or changes levels during flight. In the fuel system on an airplane, it is necessary to employ additional pump means, such as a booster pump, after the plane reaches a certain altitude and the ambient air pressure drops accordingly. The booster pump must be varied in speed in keeping with the changing conditions of flight, or the predetermined constant pressure differential over the carburetor will not be had.

With the foregoing in mind, it is an important object of the present invention to provide an automatic speed control in a fuel system arranged to maintain a predetermined constant pressure differential between the carburetor intake and its outlet to the engine, to a very fine degree.

Another object of the invention resides in the provision of a fuel system including a pressure operated speed control for a pump, which speed control operates automatically through a wide range of increments so that the proper speed will be nicely and rapidly established every time a change in speed is necessary.

A further object of the invention resides in the provision of a motor speed control which is sensitive to pressure occurring between a series of fuel pumps and a carburetor intake, and responds to variation of such pressure to maintain a proper pressure to the carburetor regardless of whether or not one or more pumps in the series are in operation.

Another object of the invention is to provide a novel speed control for an electric motor.

It is also a feature of this invention to provide an electrical motor speed control embodying variable resistance means operated automatic-

ally by a diaphragm that is responsive to changes in fluid pressure.

Another feature of the invention resides in the provision of a speed control device having a variable resistance and selection means in the form of a rocker arm with means for automatically exerting pressure on the rocker arm in a direction substantially through the point of contact at all times.

Still another feature of the invention resides in the provision of a speed control device including a variable resistance with a rocker arm selection contactor, such contactor being actuated by a fluid pressure responsive diaphragm.

15 A further object of the invention is the provision of a variable resistance controlling device including a rocker arm selection contactor with pressure exerting means movable with the rocker arm to always exert pressure in a direction through the point of contact of the rocker arm, thus giving the double advantage of positive contact and the reduction to a minimum of the driving force necessary to rock the contactor in either direction.

20 25 It is also an object of the invention to provide a variable resistance control device including a rocker arm contactor, with means to automatically maintain the same pressure on the rocker arm at its point of contact regardless of its position.

25 30 While some of the more salient features, characteristics and advantages of the instant invention have been above pointed out, others will become apparent from the following disclosures, 35 taken in conjunction with the accompanying drawings, in which:

Figure 1 is a diagrammatic illustration of a fuel supply system embodying principles of the instant invention, and illustrating diagrammatically the controlling electrical circuit;

40 Figure 2 is a central vertical sectional view through the speed control device embodied in the system of Figure 1, with parts shown in elevation, and with the portion of the necessary electrical connections illustrated diagrammatically; and

45 Figure 3 is a plan sectional view through the structure of Figure 2, taken substantially as indicated by the line III—III of Figure 2 looking in the direction of the arrows.

50 55 As shown on the drawings:

In the illustrated embodiment of this invention there is shown a fuel supply system including a fuel tank 1 having a vent 2 leading to the atmosphere. The outlet of the fuel tank 1 is in direct communication with the inlet of a booster

pump 3 driven by an electric motor 4 of which the field winding 5 is shown separated from the motor for the purpose of clarity.

The booster pump 3 discharges through a pipe 6 to the intake of a main fuel pump 7 which in turn discharges through a pipe 8 to a carburetor 9 associated with an internal combustion engine 10.

The booster pump 3 is preferably of that type wherein the inlet and outlet are always in open communication whether or not the pump impeller is in operation. The fuel pump 7 is of that type having a valved bypass interconnecting its intake and discharge. It will therefore be apparent that the carburetor 9 may be supplied with fuel from the tank 1 by either the booster pump 3 or the fuel pump 7 without the aid of the other. In the event the booster pump 3 operates alone, pressured fuel from this booster pump will be bypassed in the fuel pump 7 and delivered to the carburetor. In the event the fuel pump 7 operates alone, fuel from the tank 1 will pass directly from the inlet to the outlet of the booster pump 3 to the intake of the fuel pump 7, and pressured fuel will be delivered to the carburetor solely by the fuel pump 7.

If this fuel system is incorporated in an airplane, after the airplane reaches a certain altitude and the ambient air pressure accordingly drops, the fuel pump 7 will in all likelihood not be capable of supplying fuel under the desired pressure to the carburetor, and the fuel so supplied will contain air and vapor bubbles which interfere to a material degree with the proper operation of the engine. It is then desirable to operate the booster pump 3, and this booster pump is preferably of such character as to beat out the bubbles of gas and vapor occurring in the fuel in the tank 1 by virtue of the dropping of ambient air pressure, and deliver bubble-free fully liquid fuel under pressure to the fuel pump 7, thereby augmenting the fuel pump 7 so that liquid under the predetermined and desired pressure is supplied to the carburetor by the combined action of both pumps. Of course, in case of failure of the fuel pump 7, it will be necessary to supply the carburetor with pressured fuel by the booster pump 3 alone.

The booster pump normally operates at a single low pressure speed when assisting the engine fuel pump even though the airplane may change levels during flight. But, if there is a partial or complete failure of the fuel pump 7, the booster pump is subjected to emergency performance and must necessarily operate at a higher speed than when the fuel pump is operating efficiently. It is therefore desirable to have a highly accurate and sensitive automatic control over the speed of the booster pump motor, and a control that will vary the speed of the booster pump rapidly, efficiently, and accurately to a very wide increment range, in keeping with changing conditions.

To this end, I have provided an automatic speed control device generally indicated by numeral 11 connected in the fuel system at one end by a conduit 12 leading to the pipe 8 between the fuel pump 7 and the carburetor 9. The other end of the control device 11 is connected through a conduit or pipe 13 to the intake manifold of the engine 10, on the discharge side of the carburetor. In the fuel supply system, therefore, the control device is shunted around the carburetor so that it will be affected by pressure occurring on the intake side of the carburetor and the pressure on the discharge side of the carburetor, and, in re-

sponse to both these pressures, will maintain the proper pressure differential over the carburetor.

Referring now to Figures 2 and 3, it will be seen that the automatic control device 11 includes a composite hollow casing 14 having a head 15 at one end with a threaded opening 16 to which the pipe 12 is connected. At the other end thereof the casing 14 has a head 17 with a similar threaded opening 18 into which the pipe 13 is connected. Inside thereof, a partition 19 divides the casing into two chambers, an upper chamber 20 and a lower chamber 21. The pipe 12 communicates with the interior of the upper chamber 20 through the port 16 and a passage 22 in the head 15. The pipe 13 communicates with the lower chamber 21 directly through the port 18.

Within the casing is a reciprocable shaft 23 slidable through a bearing as indicated at 24 in the partition 19. The upper end of this shaft terminates in a hollow piston 25 reciprocable within a suitable cylinder bore 26 in the casing head 15. Just below the piston 25, the shaft is connected to a diaphragm 27 extending entirely across the chamber 20. This connection is established by means of a pair of similar upper and lower flange members 28 of sufficient area to maintain the central portion of the diaphragm fixed between them. Outside of this central portion the diaphragm is annularly arcuate so as to permit the diaphragm to respond to pressure set up in the chamber 20.

In the lower chamber 21 another and similar diaphragm 29 is mounted across the chamber, and this diaphragm is anchored to the same shaft 23 by similar flange members 30. The lower diaphragm 29 is responsive to pressure set up in the chamber 21, communicated to the chamber through the pipe 13, from the opposite side of the carburetor 9. A coil spring 31 in the lower chamber provides an initial predetermined pressure on the diaphragm 29, the pressure of this spring being augmented by pressure through the pipe 13 or detracted from by dropping of pressure in the same pipe, as the case may be. The partition 19 is preferably provided with an opening 19a to vent the space between partition 18 and diaphragm 29.

From the foregoing, it will be noted that as the pressure differential over the carburetor 9 varies, the diaphragms 27 and 29 will reciprocate the shaft 23 up and down in accordance with the variance in pressure differential. As the shaft 23 operated by the diaphragms reciprocates in keeping with variations in pressure, it exercises a fine and continuous automatic control over the speed of the booster pump motor, by means now about to be described.

A bracket 32 is mounted on a side of the casing 14 to project outwardly therefrom in fixed position. This bracket carries an insulation block 33, which may be either solid or laminated. The end portions may be closed by additional blocks 34-34. Extending through the block 33 is a series of contact elements 35, 36, 37, 38, 39, 40, 41 and 42, of which there may be any desired or suitable number. These contact elements terminate at one end flush with the bottom of a groove or track 43 formed in the upper face of the block 33. At the other end thereof, the contact members 35 to 42 inclusive are connected by conductors 44, 45, 46, 47, 48, 49, 50 and 51 respectively to spaced points along a resistance coil 52. The contact points between the respective conductors and the resistance coil may or may not

be evenly spaced, depending upon circumstances of operation. It will be seen, therefore, that if the contact member 35 is placed in circuit, only an end segment of the resistance coil 52 will be in that circuit; if the contactor 37 is placed in circuit, there will be three segments of the coil 52 in circuit, and so on until finally if the contactor 42 is placed in circuit, the entire coil will be in circuit.

In conjunction with the contact members 35 to 10 42 inclusive, a selector member is provided, and in the illustrated instance this selector member is in the form of a conductive rocker arm 53, which rides in the aforesaid groove 48 so that it is prevented from lateral displacement. Longitudinal displacement of the rocker arm 53 may be prevented by any suitable means such as a spring member 49a one end of which is secured to the block 34 in any suitable manner (not visible in Figure 2) and the opposite end to the far 20 end of the rocker arm 53. This rocker arm is actuated in a rocking motion in response to reciprocatory movements of the aforesaid shaft 23 in the casing 14.

Mounted on the shaft 23 between the diaphragm 27 and the partition 19 is a double-flanged collar 54. A toggle stud 55 having a ball-ended shank 56 is pivoted on a cross shaft as indicated at 57 with the ball-ended shank extending between the flanges of the collar 54. This stud projects through an opening 58 in the casing wall, and its outward end is provided with a socket to receive the ball-ended shank 59 of stud 60 fixedly attached to the rocker arm contactor 53. It will thus be seen that when the 35 shaft 23 moves downwardly, in the position seen in Figure 2, the rocker arm 53 will be rocked upwardly toward the topmost contact member 42, and when the shaft 23 moves upwardly, the rocker arm will be rocked downwardly toward the end-most contact member 35. During movement intermediate the extreme end positions, the rocker arm will successively contact the intermediate contact members, either in one direction or the other, depending upon the movement of the 40 shaft 23.

It is desirable to insure a positive tight contact between the rocker arm and each of the contact members 35 to 42 inclusive. To this end, a fabricated yoke 61 is attached at its end portions to the fixed insulating blocks 34-34, as indicated at 62-62. This yoke will, therefore, be fixed in position. The cross arm of the yoke is provided with an opening 63 through which a cup 64 extends. This cup has its opposite wall portions pivoted to the yoke 61 as indicated at 65 in Figure 3. The pivotal connections extend only into the respective wall portions of the cup, and not entirely through the cup, so that the cup is free to pivot relatively to the yoke 61 in the same plane as the contactor rocker arm 53.

Another and circumscribing yoke 66 has its end portions rigidly connected to the contactor rocker arm 53 as indicated at 67-67. This yoke 66 is of sufficient size to circumscribe the fixed yoke 61 in spaced relationship thereto as seen clearly in Figure 2. The cross portion of this outer yoke carries a block 68 with an inwardly extending pin 69. A coiled spring 70 is seated in the cup 64 around the pin 69 and bears against the block 68 thereby urging the cross portion of the yoke 66 outwardly and causing the contactor rocker arm 53 to seat tightly against the end of whatever contact 35 to 42 it is engaged with at the time.

It will be noted that the outermost yoke 66 is free to swing with the movement of the contact rocker arm 53, and in so swinging the spring holding cup 64 will pivot with the outermost yoke 66 relatively to the inner fixed yoke 61. In this fashion, the pressure of the spring 70 will at all times be in a direction straight through the point of contact of the rocker arm 53, regardless of the movement of the rocker arm in either direction. Thus, positive pressure of the rocker arm against the end of a contact member is assured at all times, so that excellent circuit connection is established and there is little likelihood of arcing occurring, and, as well, the driving force necessary to rock the arm is reduced to a minimum.

In Figure 1 the contactor rocker arm 53, the contact members 35 to 42, and the coil 52 are diagrammatically illustrated in an electrical circuit establishing a speed control over the motor 4 of the booster pump 3. This circuit includes line wires 71 and 72 which may lead to any suitable source of electrical energy, such as a storage battery. One side of the motor 4 is connected through conductor 73 to line wire 72. The other side of the motor is connected through conductor 74 to the motor field 5, which is in turn connected by conductor 75 to line wire 71. With the circuit thus far described, when the line wires 71 and 72 are energized, the motor will run at substantially constant speed.

The contactor rocker arm 53 is connected by conductor 76 to line wire 71. One end of the coil 52, as above explained, is connected to the end contact member 42, and the other end of the coil is connected by conductor 77 to conductor 74 on the motor side of the field winding 5 so that the coil 52 will be shunting the field winding 5 of the motor 4. A switch 78 is preferably included in the conductor 77 to selectively cut in the control device 11 when the operation of the device is deemed necessary.

In operation, the present fuel supply system together with my novel pump speed control device operates very rapidly, accurately, and efficiently. Let it be assumed that the engine 10 is being supplied with fuel from the tank 1 solely by the fuel pump 7 and conditions vary to a point such that the fuel pump 7 is not pressuring the fuel sufficiently. The booster pump 3 may then be cut in series with the fuel pump 7 to build up the pressure by closing the circuit through line wires 71 and 72. The booster pump, operating at constant low pressure speed in series with fuel pump 7, is ordinarily sufficient to properly pressure the fuel through all the upper altitudes.

However, if there is a partial or complete failure of the engine fuel pump, then it is essential that the booster pump do emergency work and operate at a higher speed sufficient to maintain a satisfactory pressure differential over the carburetor. The switch 78 may then be closed by the pilot or operator cutting in the automatic speed control device 11. As long as the pressure differential over the carburetor is satisfactory with the operation of the booster pump at constant low pressure speed, the contactor rocker arm 53 will be resting on the contact member 42 so that substantially all of the coil 52 will be in circuit, and the speed of the pump will not be altered. When there is a change in that pressure differential requiring the booster pump to operate at a higher speed, that change in pressure differential will be communicated to the control device 11 through the pipes 12 and 13. If the pressure builds up through pipe 13, the dia-

phragms 28 and 27 within the casing would be moved upwardly carrying the shaft 28 therewith, and thus rotating the contactor rocker arm 53 downwardly so that it finally rests against one of the other contact members 41 to 38 inclusive, thus cutting out a part of the coil 52, and causing the current to seek the path of least resistance and shunt itself around the field circuit 5 of the motor, thus increasing the speed of the motor.

It will be appreciated that numerous increments may be provided in the coil 52, with a contact member for each increment, so that as the pressure differential over the carburetor fluctuates, the rocker arm 53 will rock backward and forward cutting out more of the coil 52 or cutting in more of the coil 52 as the case may be, and maintaining the proper speed of the booster pump motor at all times so that the proper pressure differential is maintained over the carburetor to an extremely fine and accurate degree. The entire failure of the fuel pump 1 will not interfere with adequate operation of the fuel supply system, because the entire load will then be transferred to the booster pump and the speed of this pump is automatically regulated at all times as above described so that the proper pressure of fluid to the carburetor is maintained.

It will, of course, be understood that in the construction of my automatic speed control device, insulating bushings and insulation connections of various kinds may be used between the respective parts to avoid the described circuit from being unintentionally grounded at any points in the structure. It will likewise be understood that control switch means may be incorporated at any desired point in order to energize and de-energize either the main circuit or the auxiliary circuit from the automatic control device.

From the foregoing, it is apparent that I have provided a novel fuel supply system in which a series of fuel pumps may be incorporated, and pressured fuel supplied to a carburetor under predetermined conditions of all kinds. It will be noted that the pressure differential between the carburetor intake and the carburetor discharge to an internal combustion engine is maintained constant by pressure responsive means, regardless of whether only one or all of the pumps are operated. Further, it will be noted that the speed control device for a pump, embodied in this invention, is accurate to a very fine degree, and exceedingly positive in its action, in that little if any arcing will result from a circuit closing operation and positive pressure is exercised in a direction through the point of contact at all times. Moreover, the entire structure is not only highly efficient in use, but economical to install and operate.

It will, of course, be understood that various details of construction may be varied through a wide range without departing from the principles of this invention and it is, therefore, not the purpose to limit the patent granted herein otherwise than necessitated by the scope of the appended claims.

I claim as my invention:

1. In a pressure responsive control device, a casing, a diaphragm across said casing, a fluid conducting pipe connected to said casing on one side of said diaphragm, variable resistance means, a rocker arm selector associated with said resistance means to close a circuit through various resistance increments, means connecting the rocker arm to said diaphragm to be actuated thereby, said casing having an opening therein on the opposite side of said diaphragm from said pipe, and toggle mechanism connecting said diaphragm with said rocker arm to actuate the latter, and maintain the same pressure on the rocker arm regardless of the point of contact with said resistance means.
2. In a fluid pressure responsive control device, a casing, a pair of spaced diaphragms across said casing, means connecting said diaphragms to cause operation in unison, a fluid conducting pipe connected to said casing on the outer side of one diaphragm, another fluid conducting pipe from a different source connected to said casing on the outer side of the other diaphragm, a variable resistance, a selector associated with said resistance, and means connected with said diaphragms therebetween and extending through the casing wall to actuate said selector to close a circuit through various increments of said resistance in keeping with variations of pressure in said pipes.
3. In a fluid pressure responsive control device, a casing, a pair of spaced diaphragms across said casing, means connecting said diaphragms to cause operation in unison, a fluid conducting pipe connected to said casing on the outer side of one diaphragm, another fluid conducting pipe from a different source connected to said casing on the outer side of the other diaphragm, a variable resistance including a rocker arm selector, said casing having an opening therein between said diaphragms, and toggle means connecting the diaphragms with the rocker-arm selector to actuate the latter in keeping with variations in fluid pressure in said pipes and maintain equal pressure on the selector regardless of the point of contact with said resistance.
4. In a control device, a resistance element, a series of contact members each connected to said element at a different point therealong, a rocker-arm selector rockable over said series of contact members to close a circuit through increments of said element, means to actuate said rocker-arm, fixed means adjacent said contact members, a spring holder pivoted to said fixed means, a spring in said holder, a yoke attached to said rocker-arm selector and enclosing said spring holder and against which said spring bears, a pin on said yoke extending into said spring holder and the spring therein to cause said holder to pivot with a movement of said rocker-arm selector and maintain the spring pressure on said yoke in a direction through the point of contact between said selector and one of said contact members at all times.

RUSSELL R. CURTIS.
